United States Patent

Des. 236,707
Patented Sept. 9, 1975

236,707

BICYCLE ELECTRICAL SYSTEM CONTAINER

Arthur M. Martin, Tampa, Fla., assignor to
Needs, Incorporated, Tampa, Fla.

Filed Nov. 9, 1973, Ser. No. 414,463

Term of patent 14 years

Int. Cl. D12—11

U.S. Cl. D12—114

FIG. 1

FIG. 2

FIG. 3

FIG. 4

FIG. 1 is a perspective view of a bicycle electrical system container showing my new design;

FIG. 2 is an end elevational view thereof, it being understood that the opposite end is a mirror image of the end shown herein;

FIG. 3 is a side elevational view thereof opposite to that shown in FIG. 1; and

FIG. 4 is a bottom plan view thereof.

I claim:

The ornamental design for a bicycle electrical system container, as shown and described.
